IMPULSE TRANSMITTING DEVICE

Terrence O. Westhafer, Downers Grove, and Dan J. Dickmann, Chicago, Ill., assignors to Western Electric Company, Incorporated, New York, N. Y., a corporation of New York

Application January 6, 1938, Serial No. 183,628

7 Claims. (Cl. 179—90)

This invention relates to impulse transmitting devices and more particularly to impulse transmitting devices for use in the calling dials of automatic telephone systems.

5 It is an object of the present invention to provide a simple, rugged impulse transmitting device which is quiet in its operation.

In accordance with one embodiment of the invention, there is provided a contact controlling 10 pawl adapted to be operated by projections on a camming wheel operable under control of the dial of an automatic telephone transmitting system, which pawl is pivotally mounted and has a spring attached thereto and to an extending arm 15 of a lever pivoted on the same center as the pawl for normally tending to hold the pawl in either of two predetermined positions, depending upon the direction in which the pawl is moved. The arm to which the pawl holding spring is attached 20 is provided with means for limiting the amount of movement of the arm in two directions whereby the two predetermined positions are determined.

A better understanding of the invention will 25 be had by reference to the following detailed description when considered in conjunction with the accompanying drawing, wherein

Fig. 1 is a front elevational view of a telephone dialing mechanism, parts being broken 30 away to show more clearly the details of construction of the present invention;

Fig. 2 is a rear view of the apparatus disclosed in Fig. 1;

Figs. 3, 4 and 5 are fragmentary elevational 35 views of a portion of the apparatus shown in Fig. 1; and

Fig. 6 is a sectional view taken on the line 6—6 of Fig. 3 in the direction of the arrows.

Referring now to the drawing, wherein like 40 reference numerals designate the same parts throughout the several views, the numeral 10 designates a dial for use in automatic telephone transmitting apparatus provided with a series of finger apertures 11, whereby the dial may be rotated in a clockwise direction until the finger of the first operating dial engages a stop 12. The dial is of the type common to telephone dialing apparatus, and upon its release, will be driven in a counter-clockwise direction by a spring motor 45 (not shown), a suitable governor 13 being provided for controlling the speed of the dial in its return to normal position. The dial 10 is secured to a shaft 14 by means of a nut 15 threaded onto the end of the shaft. Carried by the shaft 14 50 is an impulse wheel or cam wheel 16 having one

wide tooth 17 and a series of ten small teeth 18 formed about its periphery. The stop 12 is fixed to a cup-shaped casing 21, which encloses the operating parts of the dialing mechanism. This mechanism includes an abutment 22 against 5 which the spring motor (not shown) will urge a stop member 23 fixed to the shaft 14. The apparatus thus far described is the apparatus common to telephone dials in general use at the present time for actuating an impulse transmitter to send 10 impulses for indicating the telephone number to which it is desired to be connected. In accordance with the present invention, a pawl, designated generally by the numeral 23, is adapted to be actuated by the teeth 18 or cam wheel or impulse wheel 16 and having a portion 24 thereof which extends into the path of the teeth 18 around the cam wheel 16 so that during the rotation of the cam wheel the teeth 18 will move the pawl 23, which is pivotally mounted between a bracket 25 15 secured to the casing 21 by screws 26 and a bracket 27 formed integrally with the casing 21. The pawl 23 is fixed to a pivot pin 28, which is mounted in apertures 30 and 31 formed in the brackets 27 and 25, respectively. A portion 33 20 of the pawl 23 extends to the rear portion of the casing 21 and carries a tubular insulator 34 on a reduced portion 35 thereof, which, when the dial 11 is moved in a clockwise direction (Fig. 1), will be moved away from a contact spring 37 normally engaging a fixed contact 38. Both the contact spring 37 and fixed contact 38 form part of 25 a spring pile-up 39, which controls the transmission of impulses for connecting a telephone subscriber with another subscriber through automatic or semi-automatic exchange. The operation of those springs in the pile-up 39 other than the contact spring 37 and fixed contact 38 does 30 not relate to the present invention and a detailed description thereof accordingly will not be given. 35

Upon the rotation of the cam wheel 16 and dial 11 in a counter-clockwise direction (Fig. 1), the portion 24 of the pawl 23 will be moved by each of the teeth 18 which had been moved past it during the clockwise rotation of the dial to cause 45 the insulator 34 to break the contact between spring 37 and fixed contact 38 each time a tooth 18 passes under the portion 24 of the pawl. The portions 40 and 41 of the pawl 23 are bent over at right angles to the main body of the pawl for 50 receiving the pin 28 and the portion 41 has extending therefrom an arm 43 to which a coil spring 44 is secured. The coil spring 44 has its other end connected to a lever 45 which is pivotally mounted upon the pin 28 and which is pro- 55

vided with a pair of depending arms 46 and 47 adapted to engage opposite sides of the bracket 25 to limit the movement of the lever 45 about the pin 28.

5 In the operation of the dialing mechanism to select a number, the dial 10 may be moved manually in a clockwise direction to bring the edge of one of the apertures 11 into alignment with the stop 12, whereupon the dial may be released and 10 will be returned to normal position, as shown in Fig. 1. During the clockwise rotation of the dial 11, the camming wheel 16 will also move in a clockwise direction, and as the first tooth 18 engages with the portion 24 of the pawl 23, the 15 pawl and the lever 44 will be rocked from the position shown in Fig. 3 to the position shown in Fig. 4, where the arm 46 will engage with the side of the bracket 25 and will thus be restrained from further movement in a counterclockwise direction. However, as the cam wheel is moved 20 further, the pawl 23 will be rocked further against the tension of the spring 44. This latter movement obviously will be slight and as the portion 25 of the pawl passes over the first tooth 18 and the succeeding teeth 18, the spring 44 will move 25 the pawl back a short distance to the position shown in Fig. 4, but will not cause the pawl to slap sharply against the next succeeding tooth 18, thereby materially reducing the amount of noise 30 made by the dialing mechanism during the clockwise rotation of the dial 10.

When the dial 10 is released, the spring motor (not shown) will rotate it in a counter-clockwise direction, and as the first tooth 18 engages the portion 24 of the pawl 23, the pawl and lever 45 will be moved to the position shown in Fig. 5, where the arm 46 will engage the bracket 25. Continued movement of the cam wheel 16 in a counter-clockwise direction will move the pawl 23 against the tension of the spring 44 and the energy 40 stored in the contact spring 37, for in the movement of the pawl 23 in a clockwise direction about its pivot, the portion 35 thereof carrying the insulator 34 will be moved into engagement with the contact spring 37 each time a tooth 18 strikes the pawl. The rotation of the cam wheel 16 back to its normal position will therefore cause the opening of the circuit between spring 37 and fixed contact 38 a number of times, dependent upon the 50 number of teeth 18 which had been moved past the pawl during the rotation of the cam wheel 16 in a clockwise direction. It will be noted that during the return of the dial to normal position, at which time the selected number of impulses are 55 transmitted by the breaking and making of the contact between the spring 37 and fixed contact 38, the portion 24 of the pawl will not be urged to snap back against a succeeding tooth 18 after it has passed over a preceding tooth, thereby rendering the operation of the dialing mechanism 60 comparatively silent.

Although a specific embodiment of the invention has been described hereinbefore, and a particular construction has been definitely described, it will be understood that adaptations and variations of the structure thus described may be made without departing from the scope of the appended 65 claims.

What is claimed is:

1. In an impulse transmitting device, a rotatable

finger wheel, a camming wheel fixed to the finger wheel, a pivoted pawl actuatable by said camming wheel, contacts operable by said pawl, and means for urging the pawl to remain in either of two predetermined positions, including a spring movable about the pawl axis. 5

2. In an impulse transmitter, a pair of impulse transmitting contacts, means for actuating one of said contacts to move it out of engagement with the other contact including a pawl, means for pivotally supporting said pawl, a spring attached to an end of said pawl, and a support for said spring pivotally mounted on the same axis as said pawl.

3. In an impulse transmitter, a pair of impulse transmitting contacts, means for actuating one of said contacts to move it out of engagement with the other contact including a pawl, means for pivotally supporting said pawl, a spring attached to an end of said pawl, a support for said spring 20 pivotally mounted on the same axis as said pawl, and means for limiting the amount of movement of said spring support.

4. In an impulse transmitter, a pawl having a cam engaging portion, a contact actuating portion and a spring engaging portion, a mounting for pivotally supporting said pawl, a lever pivoted on said mounting on the same axis as the pawl, and a spring connected to said lever and said pawl for holding the pawl in either of two predetermined 30 positions. 35

5. In an impulse transmitting device, a camming wheel normally urged to remain in one position, a pawl associated with said camming wheel for actuation thereby, a pair of impulse transmitting contacts associated with said pawl and adapted to be opened by said pawl during movement thereof by the camming wheel in one direction, means for pivotally supporting said pawl, a spring connected to said pawl, and a lever connected to said spring and pivoted about the same 40 axis as the pawl.

6. In an impulse transmitting device for automatic telephone systems, a manually actuated dial, a disc secured to said dial and having a series 45 of camming projections formed thereon, a pawl associated with said disc and adapted to be actuated by said camming projections, a support for pivotally supporting said pawl, a lever mounted on said support and pivoted on the same axis as 50 the pawl, a spring interconnecting one end of said lever and said pawl, and a pair of stops on said lever for engaging the support to limit the movement of the lever in either of two directions for holding the pawl in position to be engaged by the 55 camming projections during rotation of the disc.

7. In a telephone dialing apparatus, a rotatable disc having a plurality of camming projections thereon, a pawl supporting member, a pawl pivotally mounted in said supporting member, a lever pivoted on said supporting member, a spring interconnecting an end of the lever and a portion 60 of the pawl for urging the pawl to remain in a predetermined position with respect to the lever, 65 and a pair of stops on the lever for limiting the movement of the lever about its pivot.

TERRENCE O. WESTHAFER.
